(57) **CLAIM**

The ornamental design for a shoe outsole, as shown and described.

DESCRIPTION

FIG. 1 is a side front perspective view of a shoe showing my design;

FIG. 2 is a second side rear perspective view thereof; and, FIG. 3 is a plan view thereof.

The long-and-short broken lines are used to form an unclaimed boundary around portions of the claimed subject matter and form no part of the claim. The unshaded regions within portions that are demarcated by long-and-short broken lines form no part of the claimed design. The even-length broken lines showing the remainder of the article, are directed to the unclaimed environment, and form no part of the claimed design.
